UNITED STATES PATENT OFFICE.

CHARLES JAMES HARVEY, OF KIDDERMINSTER, ENGLAND.

PORTABLE VACUUM DUST-EXTRACTOR.

No. 908,992.

Specification of Letters Patent.

Patented Jan. 5, 1909.

Application filed June 3, 1908. Serial No. 436,511.

To all whom it may concern:

Be it known that I, CHARLES JAMES HARVEY, a subject of the King of Great Britain, residing at 9 Church street, Kidderminster, 5 England, have invented certain new and useful Improvements in Portable Vacuum Dust-Extractors; and I do hereby declare the following to be a full, clear, and exact description of the invention, such as will enable 10 others skilled in the art to which it appertains to make and use the same.

This invention relates to improvements in portable vacuum dust extracting apparatus and consists essentially in forming the base 15 or foot board of such machines with a hinged outstanding portion or platform and in combining one or more exhausters with a dust collecting contrivance also arranged as to permit of the apparatus being folded into a 20 small compass and being locked together when folded so as to be rendered more convenient for transport from one place or position to another. And in order that my invention may be fully understood I will describe same with reference to the accompanying drawings and letters and figures of reference marked thereon, that is to say:—

Figure 1, is an elevation of the device in its folded or closed state. Fig. 2, a similar 30 view showing the device showing the foot board let down in operative position. Fig. 3, a similar view showing the device showing a compression and expansion of the bellows. Fig. 4, a similar view showing the reverse 35 expansion and compression of the bellows. Fig. 5, an end elevation. Fig. 6, an end elevation opposite to Fig. 5. Fig. 7, a plan view of the apparatus. Fig. 8, a side elevation showing the apparatus folded or closed 40 for transport. Fig. 9, an end elevation showing the apparatus in its open or operative state.

Similar letters of reference indicate like parts throughout.

45 In carrying my invention into effect I use two exhausting bellows *a*, *a*, but instead of, as usual, making them double—each forming part of the other, I separate them entirely and fix them on opposite sides of the dust box 50 *b*, as seen more particularly in Figs. 1, 2, 3, 4, 7, and 8 of the drawings, and connect them

by means of the dust box *b*. Stays *c*, connect the movable outer portions of the bellows *a*, whereby the expansion of all compresses the other and vice versa.

55

The machine may be built with the hinged end of the bellows upwards or at any angle and the said bellows may be operated by hand, pedal, or motor power.

The outstanding portion *d*, of the base or 60 foot board on which the machine is built is hinged parallel to, and as near the side of the dust box *b*, as possible, and will serve as hereinafter appears as a means of locking the whole together when folded as well as a 65 steady base for pedal or motor driven machines.

Stays *e*, are provided hinged at their lower end to the edge of the hinged projecting or outstanding portion *d*, of the foot 70 board and formed with hooks *f*, or of a hooked shape at their upper or free ends to engage with eyes, or knobs *g*, or other suitable fitments provided on the machine to fix it in the open position. Similar eyes, knobs or 75 fitments *h*, are provided upon the side edges of the front bellows *a*, to which the hooked ends *f*, of the stays *e*, are attached when it is desired to keep the machine or apparatus 80 closed. These stays *e*, may further be made 85 to run in slots provided to guide them and prevent their falling about when not hooked. Or a short chain or other suitable contrivance may be provided to effect the same purpose.

85

The bellows *a*, *a*, may be operated by hand by means of the handle *i*, which will also serve (see Fig. 8) as a draw bar by which the apparatus, mounted on the wheels *k*, may be drawn or propelled from one position to another or the bellows may be operated by pedal or motor power. Tubing *l*, a nozzle *m*, and other accessories usual for the requirements of pneumatic cleaning are supplied and fitted to the apparatus in the ordinary manner.

90 95
What I claim is:—

In a portable vacuum dust extractor, the combination of a dust box, a pair of bellows mounted on opposite sides of the dust box, 100 hinged stays connecting said bellows whereby the expansion of one compresses the

other, a platform hinged to the base of the dust box, stays having one end pivoted to the platform, means for locking the free ends of the stays to the dust box when the platform is open, and means for locking said end to one of the bellows when the platform is closed.

In testimony whereof, I affix my signature, in presence of two witnesses.

CHARLES JAMES HARVEY.

Witnesses:

JAMES MORTON,
GEO. W. COOKE.
